UNITED STATES PATENT OFFICE.

JOHN H. LUX, PHILIP LUX, AND SAMUEL EDE, OF EARLVILLE, IOWA; JOHN H. LUX ADMINISTRATOR OF SAID PHILIP LUX, DECEASED.

HAY-LOADER.

SPECIFICATION forming part of Letters Patent No. 341,385, dated May 4, 1886.

Application filed June 13, 1885. Serial No. 168,569. (No model.)

To all whom it may concern:

Be it known that we, JOHN H. LUX, PHILIP LUX, and SAMUEL EDE, all residents of Earlville, in the county of Delaware and State of Iowa, have invented certain new and useful Improvements in Hay-Loaders; and we do hereby declare that the following is a full, clear, and exact description of the invention, which will enable others skilled in the art to 5 to which it appertains to make and use the same, reference being had to the accompanying drawings, which form a part of this specification, and in which—

Figure 1 is a perspective view of the lower 15 part of a hay-loader provided with our improvement. Fig. 2 is a perspective detail view of the middle portions of the rake-bars and of the guides, showing the improvement, and Fig. 3 is a perspective detail view of one 20 of the rake-bars.

Similar letters of reference indicate corresponding parts in all the figures.

Our invention has relation to endless-chain rakes for hay-loaders; and it consists in the 25 improved construction and combination of parts of the means for guiding the rake-arms and allowing them to yield to obstructions for the teeth, as hereinafter more fully described and claimed.

30 In the accompanying drawings, the letters A A indicate the drive-wheels, which are mounted upon the drive-axle B, which is journaled in bearings upon the side pieces, C C, of the machine-frame. This frame is secured 35 in the usual manner to the rear end of a wagon and has the inclined elevator-frame D, provided with the endless elevator-chains E, the cross pieces or slats F, and connecting-cords G. The wind-brake H is secured over 40 the elevator and has the longitudinal slats I, and all these parts may be of any desired construction, no claims being made for the same. Two uprights, J J, are secured upon the side pieces of the frame, and are provided near 45 their tops with gudgeons, upon which the sprocket-wheels O O are journaled. Two hangers, N N, are secured upon the lower edges of the side pieces of the frame, and a rake-shaft, L, is journaled in bearings M M 50 in these hangers and provided at its ends with

the sprocket-wheels P P. A sprocket-chain, Q, connects each of the wheels P with one of the wheels O, and a cog-wheel, R, upon the end of the shaft L, receives motion from a cog-wheel, S, upon the drive-shaft. The sprocket-chains are provided at even intervals with links T, which form transverse sockets U, and the ends of the rake-bars V turn in these sockets, the sockets forming bearings for the ends of the transverse rake-bars. 55 60

The rear ends of the side pieces of the machine-frame are connected by means of a cross-piece, W, and the lower end of the wind-brake is formed by a cross-piece, X, and a curved flat strip or bar, Y, is secured at both ends to 65 the middles of these cross-pieces, forming the lower portion of the guideways for the rake-bars. The curved cleaner rods or bars Z are likewise secured at their ends to these cross-pieces, having the same curve as the guide-strip, the said cleaner-rods serving to clean 70 the teeth A' of the rake-bars from the hay as the rake-teeth carry the hay up upon the elevator.

The upper guide strip or bar, B', is curved 75 to run parallel with the lower strip, and its upper end is secured to the middle of a cross-piece, C', secured to the lower ends of the uprights J, and the lower end of the upper guide-strip is bent forward, as shown at D', 80 and formed with a bearing, E', in which the middle of the lower rake-shaft turns, the said shaft supporting the said end of the guide-strip.

The outwardly-pointing ends of two spiral 85 springs, F', are formed into eyes G', as shown, and fit upon the two central teeth of the rake-bars, and the springs are wrapped around the rake-bars, and have their ends secured to the under sides of plates H', the said ends projecting at right angles, or nearly so, to the teeth. 90

Each plate H' is provided with a transverse eye, I', near its rear end, into which the inwardly-bent ends of the springs are placed, 95 and the springs are secured by means of a transverse yoke or clamping-plate, J', secured to the forward portion of the under side of the plate by means of a screw, K', and the side edges of the plate may be provided with 100

downwardly-projecting lips L', which prevent the ends of the springs from spreading, when two springs or a spring made in two parts is used.

5 It will be seen that when the rake-bars are at the upper portion of their journey the plates are free of the guideways, and consequently the rake-bars are allowed to swing freely in their bearings with the teeth projecting downward, and when the bars pass between the guide-bars the plates will cause the teeth to project downward, so as to bear against the ground and rake the hay, while the springs will allow the bar and teeth to yield 15 to any obstructions and force them back into their original position when the obstruction is passed. The upper sides of the plates H' bear against the upper guide-bar, while the lower guide-bar serves to prevent the springs, 20 when returning the rake-bars to their normal position after passing an obstruction, from throwing the teeth and the plates too far forward, the under sides of the plates striking the lower guide-bar in that case.

25 By using one guideway instead of two, and placing it near the middle of the machine, the spring upon each rake-bar will always act upon the rake-bar in any operative position, while if two springs are used, as would be 30 necessary with two guideways, they would have to be adjusted with relation to each other, and even then it has been found by experience that in a short time one or the other of them will get out of its proper adjustment 35 and leave that end of the rake-bar without any sufficient support, and cause the rake-bar to be twisted or racked out of position, and the machine rendered inoperative and useless.

40 The operation and advantages of our invention may be readily understood from the foregoing description, taken in connection with the accompanying drawings, without further explanation.

Having thus described our invention, we 45 claim and desire to secure by Letters Patent of the United States—

1. In an endless-chain rake, the combination of a curved guideway and a series of rake-bars, said guideway consisting of two curved bars 50 supported independently of each other, and

placed intermediate of the ends of the rake-bars, and each of said rake-bars being provided with a spring-actuated plate which travels within said guideway, as and for the purpose shown and set forth.

2. In an endless-chain hay-loader rake, the combination of a curved guideway formed by curved bars with the rake-bars having teeth, springs wrapped around the bars and secured at one end to them, and guide-plates for traveling between the guide-bars, secured to the opposite ends of the springs, as and for the purpose shown and set forth.

3. In an endless-chain rake, the combination of a curved guideway formed by curved bars, the rake-bars having teeth, springs secured thereto and having their ends projecting out at a nearly right angle to the teeth, and plates traveling in the guideway and secured to the projecting ends of the springs, as and for the purpose shown and set forth.

4. In a hay-loader, the combination of the frame having a cross-piece at its rear end, and having two cross-pieces at the lower portion of the elevator, the rake-shaft, the lower curved guide-strip secured to the uppermost and to the rearmost of the cross-pieces, the upper curved guide-strip secured at its upper end to the lowermost of the two upper cross-pieces and having its lower end bent forward 80 and provided with a bearing for the rake-shaft, and the endless chain rake passing between the guide-strips, as and for the purpose shown and set forth.

5. The combination of a guide-plate, having a transverse eye at one end and a yoke or clamping-plate secured to the other, a rake-bar, and a spring secured to said guide-plate by means of said eye and yoke and to said rake-bar, as and for the purpose shown and set forth.

In testimony that we claim the foregoing as our own we have hereunto affixed our signatures in presence of two witnesses.

JOHN H. LUX.
PHILIP LUX.
SAMUEL EDE.
